UNITED STATES PATENT OFFICE.

GEORGE J. CLARK AND HERBERT CURTLAND, OF DEFIANCE, OHIO.

METALLIC BARREL.

1,073,396.

Specification of Letters Patent. Patented Sept. 16, 1913.

Application filed August 5, 1912. Serial No. 713,337.

To all whom it may concern:

Be it known that we, GEORGE J. CLARK and HERBERT CURTLAND, citizens of the United States of America, residing at Defiance, in the county of Defiance and State of Ohio, have invented certain new and useful Improvements in Metallic Barrels, of which the following is a specification.

This invention relates to barrels and has especial reference to metallic barrels.

The invention has for its object to provide an improved metal barrel preferably formed of steel and constructed with two sections, so that the barrel is formed with only one seam.

The invention further has for its object to provide a steel barrel constructed in two sections secured together so as to provide but a single joint and render the barrel light, strong and durable.

The accompanying drawing shows a metal barrel constructed in accordance with this invention the figure being a view partly in side elevation and partly in section.

In carrying out the invention the barrel is constructed with two cylindrical sections 1, preferably of steel, and pressed so as to form a chine 2 at one end of each section, and a head 3. The edge of the open end of each section 1 is bent in so as to form an annular flange 4, and in the construction of the barrel the sections 1 are placed together with the flanges 4 of their meeting, open ends abutting together. To reinforce and strengthen the seam formed by the abutting flanges 4 a metallic annular band ring 5 is located within the barrel, and is formed with an annular groove 6, in which the abutting flanges 4 are adapted to be seated, the open flanged ends of the sections 1 being slipped over the metal band 5 into the position shown. The joint formed by the abutting flanges 4 resting in the annular groove 6 is

welded or brazed. The groove formed by the flanges 4 is thereby filled with suitable metal 11 so as to form a smooth surface on the exterior of the seam or joint formed by said flanges. Before the sections 1 are secured together, as hereinbefore described, the chines 2 may be filled with a suitable reinforcing metal, such as a metal rod 7. One of the heads 3 is provided with a suitable bung-hole 8, which can be closed by a plug, or, as here shown, by a suitable cap 9 mounted over said bung-hole.

It will be seen that a barrel constructed as hereinbefore described, with only one seam, will be strong and durable, and that leakage is avoided. By forming the half sections with a chine and head in one piece, a strong, durable barrel can be economically manufactured and will be stronger than a barrel formed in several pieces.

Having described the invention, we claim:

A metallic barrel consisting of two abutting tub-like sections, each formed in one piece with a chine and head and at its abutting end with an inturned annular flange, an annular metallic band lying within the barrel and provided with a peripheral groove 70 in which said annular flanges lie and abut, the inturning of said flanges forming a peripheral groove about the barrel and a filling of brazing material in the last named peripheral groove which brazes said flanges 75 and said band together and fills said groove to render the outer face of the barrel flush and smooth.

In testimony whereof we affix our signatures in presence of two witnesses.

GEORGE J. CLARK.
HERBERT CURTLAND.
